UNITED STATES PATENT OFFICE

2,030,675

BLOCK SIGNAL SYSTEM

Weber H. Arkenburgh, Schenectady, N. Y., assignor to General Electric Company, a corporation of New York

Application December 5, 1929, Serial No. 411,966
Renewed July 13, 1933

14 Claims. (Cl. 246—34)

My invention relates to railway block signal systems, and more particularly to railway block signal systems the operation of which is entirely electrical.

5 It has for one of its objects to provide a railway block signal system which is entirely electrical in its operation and which is operable selectively to control the block signal of a railway system as desired in signal practice and which 10 includes a single line circuit extending between adjacent blocks.

A further purpose of the invention is to provide improved means for controlling the signals in each of the blocks. Thus, in accordance with 15 my invention a signal circuit is provided in each block including a plurality of branches each of of the different signals being connected in a different branch of said circuit, together with means, which may comprise electron discharge 20 means of suitable type whereby the current in each branch is controlled as desired in accordance with track conditions. The electron discharge means provided as indicated preferably comprise a pair of vapor electric devices, or electron discharge devices of other suitable type, one of which 25 is controlled in accordance with track conditions in the block in which it is located and the other of which is controlled in accordance with track conditions in an adjacent block. These discharge devices are so connected and arranged with reference to the branches of said circuit that the energization of the different signals, or other electro-responsive devices provided in the different 30 branches are controlled by said track conditions.

In this specification I shall particularly mention the operation of the signals in accordance with track conditions and shall describe a particular means of controlling the different discharge devices in accordance with track conditions. It will 35 of course be understood, however, that I do not wish to be limited to this particular means of ascertaining the track conditions since other means may be used as well, it being essential only that the discharge devices are controlled in accordance with the occupied condition of the different blocks.

Still a further object of the invention is to provide means of the type indicated which is reliable in its operation and economical both in its initial cost and maintenance.

50 The novel features which I believe to be characteristic of my invention are set forth with particularity in the appended claims. My invention itself, however, both as to its organization and method of operation, together with further objects

and advantages thereof may best be understood by reference to the following description taken in connection with the accompanying drawings, in which Fig. 1 represents one embodiment of my invention, Figs. 2 and 3 represent modifications thereof, and Fig. 4 represents a modification of the form of the invention shown in Fig. 3.

5 Referring to Fig. 1 of the drawings I have indicated at 1 the tracks of a railway system which is divided into blocks A, B, C etc. the rails of adjacent blocks being insulated from each other in accordance with common practice as indicated at the points 2 and 3. It will be assumed for the purposes of the following description that traffic upon the track 1 passes in the direction of the arrow indicated in block A. At 4 and 5 I have indicated the signal equipment which is associated with each of the blocks B and C respectively. These equipments are identical in character and it will be understood that a similar equipment is 20 associated with each block of the railway system. For the purpose of simplification of the drawings only two equipments are represented. The usual signals corresponding to "stop", "caution" and "clear" conditions of the track are indicated at R, 25 Y and G, R', Y' and G', etc. in the equipment associated with each of the blocks. Also included in each of these equipments is a pair of electron discharge devices indicated in the equipment 5 at 8 and 9 and in the equipment 4 at 8 and 9. Also employed in each of the signal equipments is a discharge device 10, 10' etc. the function of which is, as will later be explained, somewhat different from that of the discharge devices 8, 9 and 8', 9', and which may, or may not, 30 be of the same type of device. As will be made clear in the description and as illustrated in Fig. 2 the discharge device 10, 10' may be omitted if desired.

35 The discharge devices employed may be of the heated cathode vacuum type such as are employed commonly in signal systems, although I prefer to employ vapor electric devices or devices in which the enclosing envelope is provided with a trace of mercury vapor. These discharge devices have the characteristic that as the grid is gradually made positive with respect to the cathode they suddenly become conducting and when made negative they become non-conducting at substantially the voltage at which they became conducting. That is, at a fixed value of grid voltage which is substantially unique, the impedance of the device changes from a substantially infinite value to a very low value and visa versa, and the 40 45 50 55

device is, when conducting, capable of passing a large amount of current between its anode and cathode. For these reasons the vapor electric device is particularly well adapted to the purposes contemplated since it may be made to respond to very small voltage variations, such as may occur between the rails of the railway signal system in wet weather conditions.

It will be noted from the drawings that the cathodes of the discharge devices 8, 9 and 10, 8', 9' and 10' are energized through separate secondary windings 11, 12, and 13, 11', 12' and 13' respectively, on transformers 14, 14', the primaries of which are connected across a pair of power supply conductors 15. The right-hand winding of each of the transformers 14, 14' is connected to supply electromotive force directly to the track rails of the adjacent block in the direction opposite to the direction of traffic. At the opposite end of each block this electromotive force is impressed upon the primary winding of a transformer 20, 20' through a transformer 23, 23' and amplifier 10, 10'. The secondary windings 19, 19' of transformer 20, 20' are connected to supply this potential to the grid of the associated discharge device 9, 9' respectively. This grid circuit in the equipment 4 extends from the cathode of device 9 to the midpoint of winding 12 and thence through the winding 19 to the grid of device 9. This potential is such that when supplied to the grid of device 9 this device is of very low impedance, whereas when this potential is interrupted as by a vehicle entering the corresponding block and thereby short circuiting the rails through the wheels and axles of the vehicle, the discharge device is of very high impedance.

The secondary winding 25' of the transformer 20' and, similarly, each of the corresponding windings in the different signal equipments, is connected to supply potential to the grid of device 8 in the adjacent block in the direction opposite to the direction of traffic through a circuit extending from one side of winding 25', through line conductor 24', grid and cathode of device 8, and common conductor 16 to the opposite side of the winding 25'. Thus the devices 8, 8' in the different blocks are controlled similarly with devices 9 and 9', but in response to the condition of the adjacent block in the direction of traffic.

It will now be apparent that the grid circuits of these devices are inherently safe, that is, any open circuit such as might be caused by a broken rail in the corresponding block or a short circuit of the grid circuit at any point between the supply conductors and the different grids has the same effect upon the signal system as the presence of a vehicle in the corresponding block i. e. it causes the supply of electromotive force upon the respective grids to be interrupted.

The discharge devices 8 and 9 are connected in series through a circuit which extends from the secondary winding 17 on transformer 14, anode and cathode of discharge device 9, anode and cathode of discharge device 8, signal lamp G and resistance 18 back to the opposite side of winding 17. If we assume that there is no vehicle in the block B or in block C, sufficient current will flow in the above circuit to cause the lamp G to be lighted thereby indicating a clear condition of the track.

Current also normally flows through a branch circuit extending from resistance 18 through lamp Y, resistance 21 to the cathode of device 9, the circuit being completed through device 9, and

winding 17. Similarly current flows through a second branch circuit extending from resistance 18 through lamp R and resistance 6, this circuit also being completed through winding 17.

The drop in potential on resistance 18, however, is sufficiently great to prevent signals Y and R from lighting.

The system may now best be understood by reference to its operation. When a vehicle enters the block B, for example, the primary winding 10 of transformer 23 associated with that block becomes short circuited thereby removing alternating current from the grid of amplifier 10 and hence from the grid of the device 9 and also from the line conductor 24 extending to equipment associated with block A (not shown). Thus, the above traced circuit through the signal lamp G is now interrupted by the high impedance of the discharge device 9, and the current in resistance 18 is considerably reduced. The device 9 also interrupts the circuit of lamp Y preventing that lamp from lighting. It will be noticed that signal lamp R is connected directly across the winding 17 through resistances 18 and 6. The reduction of potential on the resistance 18 causes a greater proportion of the potential of winding 17 to be impressed across the signal R in the equipment 4 and an increase of current in this branch of the circuit. This lamp is thus lighted indicating that the block B is occupied.

Let us assume that the vehicle moves from the block B into the block C. It will of course be apparent that the "clear" or "safe" signal G' associated with the block C is extinguished and the lamp R' lighted. Deenergization of the transformer 20' of the equipment 5 removed alternating current potential from the grid of the discharge device 8 in the equipment 4, and thereby causes this discharge device to become of high impedance. Alternating current is again supplied to the grid of the discharge device 9 causing this device to be of low impedance. Signal lamp R in the equipment 4 is now shunted by the above mentioned branch circuit extending through the lamp Y in said equipment, resistance 21, cathode 45 and anode of discharge device 9 to one terminal of the secondary winding 17. The current in this circuit causes the lamp Y to be lighted and sufficient drop in potential in resistance 18 to cause the lamp R to be extinguished. The lamp G at 50 this time is extinguished since the discharge device 8 which is connected in series therewith is now of high impedance. This condition of signals indicates to a vehicle operator proceeding from block A that block B is unoccupied and that block C is occupied. When the vehicle moves from block C into the next adjacent block to the left it will be apparent that the lamp G in the equipment 4 will again be lighted and the lamp Y extinguished. The lamp Y' in the equipment 5 60 will become lighted and remain lighted until the vehicle leaves said next adjacent block. It will of course be apparent that when both blocks B and C are occupied, a "danger" or "stop" signal will be given by both the equipments 4 and 5. 65

Referring now to Fig. 2 a somewhat different arrangement of the circuits is employed, although substantially the same operation occurs. In the system shown in Fig. 2 the amplifiers 10, 10' of Fig. 1 are omitted, potential being supplied 70 from the track directly through the transformers 20, 20' to the grid of the discharge devices 9, 9' respectively in the equipments 4 and 5. Alternating current potential is similarly supplied to the grid of the discharge device 8 in the equip- 75

ment 4 from a secondary winding 25' on the transformer 20' in the equipment 5 through line conductor 24' and the common conductor 16. In this figure discharge devices of the heater cathode type are indicated, although of course other types of discharge devices may be used as well. The heating circuits of the devices 8 and 9, 8' and 9' are connected to the secondary windings 11 and 12, 11' and 12' on the transformers 14, 14' respectively. The anode circuit of the discharge device in equipment 4 extends from one side of the secondary winding 17 of transformer 14 through resistance 26, cathode and anode of discharge device 9, cathode and anode of discharge device 8, and the "clear" signal G to the opposite side of the winding 17. Thus the signal G in each of the blocks is normally lighted. Connected in shunt with discharge device 8 is a branch circuit including resistance 27, and signal Y. The circuit of this branch is completed through device 9, resistance 26, winding 17, and the signal G. Similarly connected in shunt with discharge device 9 is a branch circuit comprising resistance 29 and primary winding of transformer 28, the circuit of this branch is completed through resistance 27, winding 17, and the signal G. The resistances 27 and 29 in these branch circuits and also the resistance 26 are so adjusted that the signals Y and R are not sufficiently energized to cause them to light when alternating current is supplied to the grids of the discharge devices 8 and 9 and these devices are of low impedance. The signal G is caused to light only when both of discharge devices 8 and 9 are of low impedance and maximum current flows through the signal device.

Let us assume now that a vehicle enters the block B from the block A. It will be seen that alternating current is then removed from the grid of the discharge device 9, and likewise from the line conductor 24 leading to the equipment (not shown) in the block A. The device 9 becomes of high impedance such that the green light is extinguished, and the potential drop in resistance 26 reduced. The primary winding on transformer 28, which was previously bridged by the anode-cathode circuit of the discharge device 9 is now sufficiently energized in series with device 8 and lamp Y connected in parallel, with the signal G to cause the lamp R to light thereby causing a "stop" signal to be given. The current in the lamp Y will not be sufficient to cause it to light, since the discharge device 8 in shunt therewith is still supplied with alternating currents and is of low impedance. The condition of signals in the block C remain unchanged.

Now let us assume that the vehicle passes from block B into block C. The same operations of course occur in equipment 5, viz: the lamp G' is extinguished and the lamp R' lighted at that block and at the same time alternating current is removed from the conductor 24' extending between blocks C and B thereby causing the discharge device 8 to become of high impedance. When this occurs the low impedance shunt to signal Y comprising the anode-cathode circuit of the discharge device 8, becomes one of high impedance thereby reducing the current through the lamp R and, accordingly, maintaining the reduced drop in potential in the resistance 29. An increased current will now flow through lamp Y and discharge device 9 thereby causing lamp Y to be sufficiently energized to light, thereby to provide a caution signal to vehicles approaching from block A. When the vehicle

moves into the block to the left of block C normal conditions are restored in the equipment 4 and the caution signal is given in equipment 5.

In the equipment indicated in Fig. 1 resistances 6, 21 and 6', 21' are shown connected in series with signal lamps R, Y and R', Y' and other resistances 41 and 42 in shunt to lamps Y and G. These resistances are of value such that the signal lamps may all be of equal impedance. The resistance 42 is inserted to reduce the impedance of the circuit branch including lamp G so that when it is lighted the yellow lamp is extinguished, and similarly the resistance 41 is inserted to reduce the impedance of the branch including the lamp Y so that when it is lighted the red lamp R is extinguished. It will immediately be seen therefore that if when the lamp G is lighted, it burns out, the yellow lamp Y will be lighted; and similarly if when the yellow lamp Y is lighted, it burns out, the red lamp becomes lighted. When the red lamp R burns out, no signal is given. This is what is known as "progressive failure" of the signals. That is, upon failure of any signal an indication is given which is more restrictive to vehicles than would be given if the apparatus functioned properly. While if the red lamp R burns out no signal is produced, it is to be noted that the absence of a signal is the most restrictive indication given, being even more restrictive than the red signal.

Similarly in the equipments shown in Fig. 2, the caution and clear signals Y and G have resistances connected in parallel therewith and the caution and clear signals have resistances in series therewith for the same reason to permit the use of lamps of equal impedance. Preferably the transformers 20 of the systems of Figs. 1 and 2, have permalloy cores such that the core becomes saturated upon a comparatively small portion of the voltage normally supplied thereto. It will be apparent that when transformers of this type are employed the system is rendered comparatively insensitive to variations in the voltage normally applied to the track.

In these figures the clear signal is normally indicated in each of the blocks, this indication being changed to stop when a vehicle enters a particular block, and to caution when the vehicle leaves the block and enters the next block in advance of the vehicle provided no other vehicle enters the former block. These results are effected, it will be noted, by means employing a single line circuit extending between adjacent blocks.

In Fig. 3 I have shown means whereby the various changes in signals may be effected by means employing a single electron discharge device in each block and a single line circuit extending between adjacent blocks. In this figure the signals are all normally extinguished and are changed upon the approach of a vehicle in accordance with track conditions in the block in advance of the vehicle.

Referring to Fig. 3 I have shown discharge device 38 in the equipment 4 and device 38' in equipment 5. The anode and cathode circuits of these discharge devices are supplied from the secondary winding of the transformers 14, 14' as was the case in the previous figures and, the circuits of the different signal lamps are energized in parallel circuits through transformers 30, 30' from the secondary winding 17, 17' of transformer 14, 14'. The circuit of the equipment 4 and, similarly, of each of the other equipments, including the secondary winding 17 and 75

the primary winding of the transformer 30 includes also a resistance 31, the opposite ends of which are connected to the two rails of the adjacent block in the direction opposite to the direction of traffic. The value of this resistance is such that normally insufficient electromotive force is supplied, to the primary winding of the transformer 30 to cause lamps R, Y and G; R', Y' and G' to be lighted, although when the block 5 to the right of the respective signal system is occupied by a vehicle, this resistance becomes short circuited and sufficient electromotive force is supplied to the transformer 30 to cause the lamps to light under certain predetermined conditions presently to be described.

In the drawings the elements 32, 33, 34, 35 and 36 in the equipment 4 and the corresponding elements of the equipment 5 are reactors of the saturated core type. These reactors are shown with a bar adjacent the direct current winding to render this winding of the reactors distinctive in the drawings. These reactors may be of any well-known construction, but are of a type such that when direct current flows in one of the windings thereof, which I will call the direct current winding, of sufficient value to saturate the core; the other winding, which I will call the alternating current winding, is of very low impedance to alternating current, whereas when there is no direct current flowing in said winding and the core is unsaturated, the alternating current winding is of very high impedance. The direct current windings of each of these reactors are normally energized as will presently appear, and accordingly, their alternating current windings are of very low impedance to alternating current. It will be seen from the drawings that the alternating current winding of the reactor 32 is connected in parallel with the lamp R. The impedance of this winding when direct current is flowing in the primary circuit is such that the lamp R is prevented from lighting that is, it is virtually short circuited. Similarly it will be seen that the secondary winding of the reactor 33 is connected in parallel with the lamp Y and, accordingly, this lamp is, in effect, short circuited. The alternating current winding of reactor 34 is connected in series with the lamp Y and a limiting reactor 37 but, since the lamp Y is short circuited, it does not become energized. The reactor 37 prevents an excessive current from flowing in the circuit. The alternating current windings of reactors 35 and 36 are both connected in series with the lamp G, and are normally of low impedance, but since, as may be assumed, there is no vehicle in the block A, the resistance 31 is not short circuited and, accordingly, the lamp G is not lighted.

Let us now assume that a vehicle enters the block A and that blocks B and C are unoccupied. Resistance 31 is short circuited by the vehicle, and the lamp G becomes lighted. Lamps R and Y will not be lighted for reasons already explained.

The anode circuit of the discharge device 38, which is identical with the anode circuit of each of the other discharge devices, can best be understood by tracing the circuit of discharge device 38' since this circuit is completely illustrated in the drawings. This circuit extends from the cathode of discharge device 38' through the direct current windings of the reactors 34', 38' and 32' in the equipment 5, line conductor 24' extending between blocks C and B, direct current windings of reactors 33 and 35 in the equipment 4, thence

over the common conductor 16 and middle secondary winding of transformer 14' to the anode of discharge device 38'. Thus the anode circuit of the discharge device 38 extends from the cathode thereof through the direct current windings of reactors 34, 36 and 32, and thence to the equipment (not shown) associated with the block A after which it returns through the common conductor 16 and the middle winding of the transformer 14 to the anode of the discharge device 38.

Now let us assume that the vehicle enters block B and leaves block A unoccupied. The resistance 31' becomes short circuited and, since the discharge device 38' is energized, the lamp G' will become lighted thereby indicating a safe condition in the advance block C. Alternating potential is now removed from the grid of the discharge device 38 and this device becomes of high impedance, thereby interrupting current in the direct current windings of reactors 34, 36 and 32. The alternating current winding of reactor 32 now becomes of high impedance, but the lamp R will not be lighted, for the reason that the block A is unoccupied and the resistance 31 is not short circuited. If a vehicle now enters block A, the resistance 31 will be short circuited and sufficient energy will be supplied to the transformer 30 and thence through limiting reactor 39 to cause the red lamp R to be lighted, thereby informing the vehicle operator in block A that the advance block is occupied. Thus with a vehicle in both block B and block A, the lamp G' will be lighted in the equipment 5 and the lamp R will be lighted in the equipment 4.

Let us assume that the vehicle in block B now enters block C. The discharge device 38' now becomes of high impedance thereby deenergizing the direct current windings of reactors 34', 36' and 32' in the equipment 5 and reactors 33 and 35 in the equipment 4. No signal is lighted in equipment 5, however, since the resistance 31' is not short circuited, the block B being unoccupied. Potential is again supplied to the grid of discharge device 38, thereby causing the direct current windings of reactors 34, 36, and 32 in equipment 4 to be energized. Since resistance 31 is now short circuited, lamp Y will be lighted in equipment 4, and the lamp R will be extinguished since it is now short circuited by the secondary winding of reactor 32. The lamp G will not be lighted since the direct current winding of reactor 35 is deenergized.

It will thus be seen that in this system the signals are normally deenergized, but that as the vehicle proceeds along the track the signals associated with the block immediately in advance will indicate "safe" if the corresponding block and the next adjacent block are both unoccupied. If the block immediately in advance of the vehicle is unoccupied and the next adjacent block is occupied, the signals in the block immediately in advance of the vehicle indicate "caution." If the block immediately in advance is occupied its signal indicates "danger." The danger signal in the block occupied by a vehicle is not given except when the block immediately to the rear of the vehicle is occupied. The caution signal in any block will be given only when both adjacent blocks are occupied and the block in which the signal is located is unoccupied.

If desired the arrangement shown in Fig. 3 may be modified as shown in Fig. 4 by eliminating transformer 30 and energizing the signal 75

circuits directly from the winding 17 on transformer 14. The resistance 31 and connections thereto leading from the track circuit are omitted. As thus modified it will be seen that the clear 5 signals will be normally lighted and will be extinguished by a vehicle occupying the corresponding block thereby causing the stop signal to be lighted, or by a vehicle entering the advance block thereby causing the caution signal 10 to be lighted.

While I have shown a particular manner of supplying the control electromotive force to the discharge device, it will of course be understood that this may be effected in any other suitable 15 way, it being necessary only that the condition of the discharge device be altered by the presence of the vehicle in the particular block with which the signal is associated.

While I have shown particular embodiments of 20 my invention, it will of course be understood that I do not wish to be limited thereto since many modifications, both in the circuit arrangement and in the instrumentalities employed, may be made, and I therefore contemplate by the appended claims to cover any such modifications 25 as fall within the true spirit and scope of my invention.

What I claim as new and desire to secure by Letters Patent of the United States, is:

30 1. The combination, in a railway block signal system of a plurality of discharge devices in each block of said system, a plurality of signal devices in each block, a source of electromotive force, a circuit including said discharge devices connected in series relation and said source of electromotive force, said circuit having a plurality of branches, one of said signal devices being included in each of said branches, and means including said discharge devices for so controlling said branches that said signal devices indicate conditions in the different blocks.

2. The combination in a railway block signal system of a plurality of series connected discharge devices in each block, a line circuit extending between adjacent blocks, one of the discharge devices in each block being connected to respond to conditions in the respective block and the other discharge device being connected to respond to conditions in said line circuit, means in the adjacent block for controlling the condition of said line circuit in accordance with the conditions in said block, clear, caution, and danger signals in each block, and means for selectively operating any one of said signals in response to the impedance of said discharge devices.

3. In combination, a circuit including an electroresponsive device and a plurality of series connected electron discharge devices, a plurality of branch circuits, each of said branch circuits including an additional electroresponsive device and certain of said electron discharge devices, and means for controlling the impedance of said discharge devices thereby selectively to operate 60 said electroresponsive devices.

4. In combination, a circuit including a plurality of series connected discharge devices and a source of electromotive force variable dependently upon the impedance of said circuit, a plurality of shunt connections to said circuit, an electroresponsive device in each of said shunt connections, said shunt connections being arranged for selective energization in response to the conductivity of said discharge devices and 70 means for controlling said discharge devices 75

thereby selectively to operate said electroresponsive devices.

5. The combination in a railway block signal system of a circuit in each block including a signal device and a plurality of series connected electron discharge devices, a plurality of branch connections to said circuit, a signal device in each of said branch connections, means responsive to the track conditions in said block for controlling one of said discharge devices, means responsive to the track conditions in an adjacent block for controlling another of said discharge devices, said branch connections being so connected and arranged that said signal devices are selectively controlled in accordance with the condition of 15 said discharge devices.

6. The combination, in a railway signal system of a plurality of signals in each block, a circuit including a source of electromotive force variable dependently upon the impedance of the circuit, 20 a plurality of series connected discharge devices arranged to control said impedance, shunt circuits about said discharge devices, one of said signals being included in each of said shunt circuits, and means responsive to track conditions 25 in each of a plurality of blocks to control said discharge devices thereby to cause operation of said signals in response to variations in said source.

7. The combination, in a railway block signal 30 system of a source of electromotive force in each block, a plurality of electron discharge devices connected in series across each of said sources, means for controlling the conductivity of one of said discharge devices in each block in response 35 to track conditions in the respective block and means for controlling another of said discharge devices in response to track conditions in an adjacent block, and a shunt circuit around each of said discharge devices, each of said shunt circuits including a signal device, and impedances so connected in circuit with said discharge devices and signals that said signals are selectively operated in accordance with the conductivity of 40 the different discharge devices. 45

8. The combination, in a railway block signal system of a circuit in each block comprising a source of electromotive force, a pair of normally conducting discharge devices and a normally actuated signal device all connected in series, means 50 to render one of said discharge devices of each pair nonconductive in response to track conditions in the respective block and to render the other of said devices nonconductive in accordance with track conditions in an adjacent block, 55 and additional signal devices connected in shunt paths about said discharge devices, the regulation of said source and the impedance of said shunt paths being so proportioned that when either of said discharge devices is nonconductive 60 the energization of said normally energized signal device is substantially reduced and one or another of said additional signal devices is actuated dependent upon which of the discharge devices is nonconductive. 65

9. The combination, in a railway block signal system of a circuit in each block comprising a source of electromotive force, a signal device, and a pair of electron discharge devices all connected 70 in series, and a plurality of shunt paths to said circuit, each of said paths including an additional signal device, and impedances so distributed in said circuit and shunt paths thereto that said signal devices are selectively actuated in accord- 75

5 ance with the conductivity of said discharge devices, and means for controlling the conductivity of one of said discharge devices in each block in accordance with track conditions in the respective block and the conductivity of the other of said discharge devices in accordance with track conditions in an adjacent block.

10. In a railway block signal system, the combination of clear, caution and danger signals in each block, means all of the component parts of which are stationary with respect to each other for energizing the danger signal when the respective block is occupied and for selectively energizing the caution and clear signals dependent upon the track condition of an adjacent block, said means including means responsive to failure of any of said signals to produce an indication which is more restrictive than the indication produced by the signal which failed all of the component parts of said last means remaining stationary with respect to each other during said response to said failure.

11. In a block signal system, the combination of a circuit in each block having a plurality of branches, clear, caution and danger signals connected respectively in different branches of said circuit, and means all of the component parts of which are stationary with respect to each other for so controlling said circuit branches that different of said signals are energized in accordance with different track conditions in the respective block and an adjacent block, and means operable when any one of said circuit branches is opened thereby disabling the respective signal to produce a more restrictive indication than is produced by the signal in the opened branch, all of the component parts of said last means remaining stationary with respect to each other during operation thereof to initiate said more restrictive indication.

12. In a railway block signal system, comprising a plurality of blocks, the combination of clear, caution and danger signal lamps in each block, means all of the component parts of which are stationary with respect to each other for selec-

tively controlling said signal lamps to cause the different lamps to be lighted in response to different corresponding conditions of the track in the respective block and an adjacent block, and means responsive to failure of any one of said lamps to give a more restrictive indication than is given by the lamp which failed, said last means operating while all of said component parts remain stationary.

13. In a railway block signal system, comprising 10
a plurality of blocks, the combination of clear,
caution and danger signal lamps in each block,
means all of the component parts of which are
stationary with respect to each other for selectively
controlling said signal lamps to cause the 15
different lamps to be lighted in response to different
corresponding conditions of the track in the
respective block and an adjacent block, and means
so arranged that when the clear lamp burns out
the caution lamp is lighted, when the caution 20
lamp burns out the danger lamp is lighted, and
when the danger lamp burns out all of said lamps
are deenergized, said last means operating while
all of said component parts remain stationary.

14. The combination, in a block signal system, of a circuit network in each block including clear, caution and danger signal devices in different portions thereof, and a source of electromotive force for energizing said devices, means entirely electrical to control the electromotive force supplied to said different portions to energize the danger signal device in response to track conditions in the respective block, and to selectively energize said clear and caution signal devices in accordance with track conditions in an adjacent block, and means comprising impedances in the different portions of said network so arranged that in response to failure of the clear signal device the caution signal device becomes energized from said source, and in response to failure of the caution signal device the danger signal device is energized from said source, said last means operating while all of its component parts remain relatively stationary. 25 30 35 40
